(57) **CLAIM**

The ornamental design for a light fixture, as shown and described.

DESCRIPTION

FIG. 1 is a bottom, front, left perspective view of a light fixture showing my new design;

FIG. 2 is a top, front, left perspective view thereof;

FIG. 3 is a bottom plan view thereof;

FIG. 4 is a top plan view thereof;

FIG. 5 is a rear elevation view thereof;

FIG. 6 is a front elevation view thereof; and,

FIG. 7 is a left side elevation view thereof, the right side elevation view being identical thereto.

The broken line showing is for the purpose of illustrating unclaimed portions of the article and forms no part of the claimed design.
